United States Patent Office.

ALFRED KUSENBERG OF PHILADELPHIA, PENNSYLVANIA.

Letters Patent No. 85,528, dated January 5, 1869.

IMPROVED DEVICE FOR FEEDING CENTRIFUGAL SUGAR-DRAINING MACHINES.

The Schedule referred to in these Letters Patent and making part of the same.

To all whom it may concern:

Be it known that I, ALFRED KUSENBERG, of Philadelphia, county of Philadelphia, and State of Pennsylvania, have invented a new and useful Improved "Device for Feeding Centrifugal Sugar-Draining Machines;" and I do hereby declare that the following is a full, clear, and exact description thereof, reference being had to the accompanying drawing, and to the letters of reference marked thereon.

My invention consists in arranging an elevated railway, on which is placed and runs a truck or car provided with a decanting-bucket, the truck being propelled by means of an endless chain passed over two chain-wheels, motion being given by means of a crank attached to one of the wheels.

The advantages of my invention are as follows:

First, it can be used where overhead-railways would be impracticable, on account of the belting or other obstructions, thereby saving space, which otherwise could not be utilized.

Secondly, it can be operated at a great saving of labor, and with perfect safety. The person who propels the truck and bucket remains stationary, and the latter (the truck and bucket) are not in the range of the men who attend the machines.

Thirdly, the operator has complete control over it while decanting the purging mass into the centrifugal machines.

Heretofore it has been customary to feed centrifugal machines by means of a swinging bucket, pushed by hand, on a railway suspended directly over the machines. This is impracticable when the machines are driven from overhead, as the belting would interfere with the railway and bucket, or the railway and bucket would interfere with the operators. To obviate this, and at the same time to allow the machines to be easily charged and scooped out by a person standing in front of the machines, I employ this device.

To enable others skilled in the art to make and use my invention, I will now proceed to describe it.

Figure 1 is a side elevation of my improved device.

Figure 2 is a plan view of same, with the centrifugal draining-machines shown.

Figure 3 is an end elevation of same.

The railway-rails R and R' are elevated by feet of the proper length, so that the top of the rails will come a short distance above the top of the centrifugal machines, the whole being thoroughly braced and secured to the floor.

The said rails R and R' are placed on one side, and on a line with the machines, and are made sufficiently long to suit any number of machines.

Secured near the ends of the rail R' are two studs, S and S', on which are placed and work two chain-wheels, W and W', the wheel W' having secured to it a crank, K.

The truck T is made in the shape as shown in the

drawing, and is mounted on wheels w, w', w'', and w''', grooved to fit the rails R and R', on which they run.

The framing of the truck T is made with the top and one side open, in which is placed the bucket B, made of copper or any other suitable metal.

The said bucket is suspended on top of the truck by means of two flanges, F and F', which are partially toothed, and work in corresponding openings made in the top of the framing.

The flanges F and F' are also made with projecting handles h and h'.

The bucket B is connected with the flanges F and F', by means of rivets or bolts and the central rod C, the ends of which project through the ends of the bucket, and through the centre of the flanges, and is held in position by nuts placed on the outside of the flanges.

The rod C is also made with shoulders or collars, which bear against the inside of the bucket B, and tend to strengthen the same.

One side of the bucket B is made with a projection in the centre, in the form of a spout, and the corners covered over a short distance on top, in order to insure the pouring of the material without spilling. The bucket B is suspended a short distance from the centre of the flanges, or eccentric to them, so as to secure the greater weight on one side, and the resting of the bucket against the back of the truck T.

Wheels w'' and w''' are placed further apart, longitudinally, in order to allow space for the bucket B.

The truck T is made with projecting ledges l and l', which extend under the outer rail, R, and prevent the truck from upsetting.

On top, and at each end of the framing of the truck, are formed two eyes, for the purpose of receiving the ends of the chain E after it is passed over the wheels W and W'.

The operation of the device is as follows:

The truck T is placed so that the bucket B will come directly under the chute or canal which extends from above, to receive the proper quantity of the purging mass or green sugar.

The crank K is now turned, which, by means of the endless chain E, propels the truck T to any centrifugal machine about to be charged.

The operator now takes hold of one of the handles, h or h', and presses it over (the teeth on the flanges F and F' working into corresponding openings on the framing) gradually, which decants the bucket B, and at the same time draws it towards the centre of the machine, as shown by dotted lines, fig. 3. When in this position it will be drained perfectly, and the contents discharged into the centrifugal machine without touching the upper flange of the revolving drum.

After the bucket is discharged, it will assume its original position on the truck, owing to its being eccentric, and is drawn back again by means of the crank

K, the operator never leaving the crank, or exposing himself to the fast-running belts; neither does he endanger or hinder the men (engaged in scooping out the centrifugal machines) by the travelling bucket.

Having thus described my invention, its construction and operation,

What I claim, and desire to secure by Letters Patent of the United States, is—

1. The arrangement of the truck T with its wheels w , w' , w'' , and w''' , projecting ledges l and l' , bucket B,

flanges F and F', and handles h and h' , constructed and operating in the manner and for the purpose set forth.

2. The within-described device for feeding centrifugal sugar-draining machines, composed of the elevated rails R and R', chain E, chain-wheels W and W', crank K, truck T, and bucket B, constructed and operating in the manner and for the purpose specified.
